UNITED STATES PATENT OFFICE.

EDWIN EUGENE CURRIER, OF CHICAGO, ILLINOIS, ASSIGNOR TO UNITED SHOE MACHINERY COMPANY, OF PATERSON, NEW JERSEY, A CORPORATION OF NEW JERSEY.

FEED-POINT OR AWL FOR SHOE-SEWING MACHINES.

No. 904,604.

Specification of Letters Patent.

Patented Nov. 24, 1908.

Application filed March 4, 1907. Serial No. 360,315.

To all whom it may concern:

Be it known that I, EDWIN EUGENE CURRIER, citizen of the United States, residing at Chicago, in the county of Cook and State of Illinois, have invented certain new and useful Improvements in Feed-Points or Awls for Shoe-Sewing Machines; and I do hereby declare the following to be a full, clear, and exact description of the invention, such as 10 will enable others skilled in the art to which it appertains to make and use the same.

The present invention relates to an improved feed point or awl for shoe sewing machines and is designed primarily as an 15 improvement on the feed point which has heretofore been used in the well known Goodyear welt and turn shoe sewing machine. In the Goodyear welt and turn shoe sewing machine, above referred to, the feed point is 20 formed integrally with a plate which is removably secured to the lower end of the feed point lever by bolts passing through the plate and the lever.

The object of the present invention is to 25 provide a feed point which can be more easily removed for sharpening than the feed point which has heretofore been used, which is less expensive to replace when worn out, which can be used for a much longer time 30 before the substitution of a new point is required, and which can be readily adjusted so as to engage the work in the desired manner.

With the above objects in view the present 35 invention consists in the improved feed point and the means for securing it to the feed point lever, hereinafter described and claimed.

The present invention will be clearly understood from an inspection of the accompanying drawings in which

Figure 1 is a view in side elevation, the cam shaft being shown in section, of a Goodyear welt and turn shoe sewing machine with 45 the present invention applied thereto. Fig. 2 is a detail view in side elevation of the lower end of the feed point lever with the improved feed point secured thereto. Fig. 3 is a view in front elevation of the parts illustrated in Fig. 2. Fig. 4 is a detail sectional view taken on the line 4-4 of Fig. 2, and Fig. 5 is a view in side elevation of one of the clamping plates by which the feed point is secured to the feed point lever, the bolt

which passes through the slot in the plate 55 being shown in section.

With the exception of the feed point hereinafter described, the machine illustrated in Fig. 1 is substantially the same in all essential particulars as the machine illustrated 60 and described in the patent to French and Meyer, No. 412,704, dated October 8, 1889, 1 indicating the curved hook needle, 2 the needle guide, 3 the channel guide, 4 the looper, 5 the take-up, 6 the thread-finger, and 65 7 the back rest.

In the illustrated embodiment of the present invention the feed point is separate from the means by which it is secured to the feed point lever and preferably consists of a wire 70 8 sharpened to a triangular point 9 at the end which engages the work. To secure the feed point to the feed point lever 10 two clamping plates 11 are provided, in the adjacent faces of which a groove 12 is formed 75 to receive the shank of the feed point. The clamping plates 11 are secured to the lower end of the feed point lever by means of bolts 13 and 14 which pass through the openings in the plates and in the lower end of the 80 lever. At one end the bolts 13 and 14 are provided with heads 15 and 16 which bear against the outer clamping plate 11 and at the other end the bolts are provided with screw-threads which are engaged by clamping nuts 17 and 18. The bolts 13 and 14 thus serve both to secure the clamping plates to the lever and to actuate the clamping plates to grip the feed point.

It is desirable in sewing machines of the 90 class to which the present invention relates that means be provided whereby the feed point can be angularly adjusted to bring it into the proper position with relation to the needle. To secure this result in the construction illustrated in the drawing the openings in the plates 11 through which the upper bolt 13 passes, is elongated, as clearly shown in Figs. 2 and 5, so that an angular adjustment of the clamping plates and of the feed 95 point, about the axis of the lower bolt 14, is permitted.

It will be noted that in the construction illustrated in the drawing both clamping bolts are actuated by means of similar nuts 100 and that these nuts are upon the same side of the lever 10 where they are readily accessible. To enable the nuts to be readily

turned when it is desired to either loosen or tighten the clamping plates, the portion of the bolt 13 which passes through the slots in the plates 11, is squared, so that the bolt is held from turning, and the head of the bolt 14 is provided with a pin which enters a hole in the outer plate 11 so that the bolt 14 is also prevented from turning.

By loosening the nut 17 on the upper bolt 13 the clamping plates can be angularly adjusted to bring the feed point into the desired position with relation to the needle, and by loosening both nuts 17 and 18 the feed point can either be removed for sharpening or can be adjusted longitudinally. Neither the angular adjustment or the longitudinal adjustment of the feed point, or its complete removal, necessitates removing the clamping plates from the machine so that the desired adjustments can be made or the feed point removed, sharpened and replaced with very little trouble. The feed point is extremely durable and will last for a long period of time since the wearing away of the point by grinding can be compensated for by adjusting the feed point longitudinally.

The invention having been thus described, what is claimed is:—

- 30 1. A shoe sewing machine, having, in combination, a feed point, a feed point lever, clamping plates engaging the feed point constructed to permit a longitudinal adjustment of the feed point, and means for securing the plates to the lever while permitting an angular adjustment of the plates.
- 35 2. A shoe sewing machine, having, in com-

bination, a feed point, a feed point lever, clamping plates receiving the feed point between them, and bolts for actuating the 40 clamping plates and for securing said plates to the feed point lever passing through openings in the plates and lever and held from rotation by the plates.

3. A shoe sewing machine, having, in combination, a feed point, a feed point lever, clamping plates engaging the feed point, a clamping bolt about which the plates are angularly adjustable passing through the plates and lever, and a bolt for securing the 50 plates in adjusted position rigid with relation to the lever.

4. A shoe sewing machine, having, in combination, a feed point, a feed point lever, clamping plates receiving the feed point between them, and clamping bolts passing through the clamping plates and lever and serving both to actuate the clamping plates and to secure said plates to the lever.

5. A shoe sewing machine, having, in combination, a feed point, a feed point lever, clamping plates engaging the feed point, and means for securing the plates to the lever while permitting an angular adjustment of the plates, comprising a bolt passing through slots in the plates and through the lever and held from rotation by said slots.

In testimony whereof I affix my signature, in presence of two witnesses.

EDWIN EUGENE CURRIER.
